CLAIM

I claim the ornamental design for a pocket hole jig, as shown and described.

DESCRIPTION

FIG. 1 is a perspective view of the pocket hole jig;

FIG. 2 is a perspective view thereof;

FIG. 3 is a rear view thereof;

FIG. 4 is a front view thereof;

FIG. 5 is a side view thereof;

FIG. 6 is a side view thereof showing the side opposite that shown in FIG. 5;

FIG. 7 is a top view thereof; and,

FIG. 8 is a bottom view thereof.

The broken lines show portions of the pocket hole jig that form no part of the claimed design.

1 Claim, 7 Drawing Sheets
